UNITED STATES PATENT OFFICE

2,680,481

FOLDABLE CLOSURE FOR OPENINGS IN WALLS

Stanley J. McCarthy, Indianapolis, Ind.

Original application March 11, 1949, Serial No. 80,906. Divided and this application September 12, 1952, Serial No. 309,280

3 Claims. (Cl. 160—206)

1

The present application is a division of my copending application Serial Number 80,906 filed March 11, 1949, now U. S. Patent 2,616,497 and relating to a "Foldable Closure for an Opening in a Wall."

This invention relates to a foldable closure for an opening in either the interior or exterior wall of a building and includes an overhead trackway and a door formed of a plurality of sheets foldable one upon the other to practically parallel relation when the door is open, the sheets having overlapping edges and rollers for supporting the sheets, and a trackway for the rollers.

These and other objects and features of the invention are hereinafter more fully described and claimed and shown in the accompanying drawings in which—

Fig. 1 is an elevation showing the door in closed position.

Fig. 2 is a plan view of the upper edge of 20 the door taken on line 2—2 of Fig. 1.

Fig. 3 is a section taken on line 3—3 of Fig. 1.

Fig. 4 is a section taken on line 4—4 of Fig. 1.

Fig. 5 is a section showing a plan view of the hinge element.

Fig. 6 shows the parts in folded relationship.

Fig. 7 is a section taken on line 7—7 of Fig. 1 showing the trackway for the rollers.

Fig. 8 is a section taken on line 8—8 of Fig. 1 showing means for connecting a roller member with a section of the door.

Fig. 9 is a front elevation of a building such as a garage showing a closure member moved to the top of an opening.

Fig. 10 is an elevation showing the door sections as being foldable in a vertical plane.

Heretofore closures for an opening are moved horizontally or vertically to open the doors and, as such doors have considerable weight, it is somewhat difficult to lift the door or move it horizontally to open position.

With my improved door closure the sheets or sections thereof are moved successively to practically parallel relation at one side of the door opening to permit ingress or egress of persons. By my improved door structure the leaves are foldable one at a time to parallel relation to one side of the door opening.

In the preferred construction shown in Fig. 1, the side members are shown at 1 and 2 and the 50 overhead member of the door opening is indicated at 3 and to the under side of the member 3 is a trackway 4 which is of rectangular form in cross section, the lower wall of which is shaped to provide a slot 5 between upturned ends 6 and 55

between the upturned ends and respective side walls are rollers 7 and 8 connected to a shaft 9 onto which the rollers are rotated. The shaft 9 is apertured to receive the pin like element 10 and the rollers are rotatable on the shaft 11 in closing or opening the door. Between the upper edge of the door sections and the rail 4 are a series of links 13, pivoted together as by means of pins 14, in end to end relation and at one end 10 a half link 15 is pivoted to a bracket 16 which, as shown in Fig. 1, extends practically the full height of the door opening.

The door is preferably formed of sheet metal which consists of a series of sheets 17 to the upper edge of which is secured a bracket 18 and to the bracket is secured a pin 10 with which the rollers are connected. Thus the door elements are suspended.

As shown more clearly in Fig. 5, the strips 17 have the edges 19 in overlapping relation. As will be realized from Fig. 7 there is a space between the upper end of the door and the trackway and preferably a fabric strip 20 is positioned on the inner side of the trackway to prevent flow of air between the lower edge of the trackway and the upper end of the sheets 17. The lower ends of the sheets 17 are in pivotal relation as indicated at 21 in Fig. 1.

As shown in Fig. 2 the sheet 23 at the free edge 30 may be turned about a vertical rod 18' and a hand hold 22 provided on the outer side of the free end of the door and a similar member 22' is provided on the inner side of the free end of the door by means of either of which the door 35 may be closed after the manner indicated in Fig. 6.

It is to be understood that the door elements may be moved horizontally as shown in the drawing but the door may be moved vertically from the floor line as indicated in Fig. 9. The functional relationship of the parts is the same in either manner of use of the door.

Each of the door sections 17 which form a part of the foldable closure have longitudinal edge portions upon opposite sides and which are curved outwardly in opposite directions as shown in Figs. 2 and 3 of the drawings. When assembled the corresponding curved edges of adjacent door sections are arranged in overlapping engagement with each other whereby there will be no open spaces between the respective sections either when the closure is open or expanded to closed position.

The respective sections 17 are joined to each other at their tops and bottoms, there being pro-

3

vided outwardly projecting flanges 24 in parallel spaced relation which are arranged normally of the general plane of the section and are upon the side thereof corresponding to the direction of the adjacent curved portion.

The respective flanges upon one side of a section are arranged in overlapping relation with the corresponding adjacent flanges of the adjacent section and are pivotally or hingedly joined to each other by the rivets 21 as shown in the drawings. The aforesaid flanges are formed by extensions of the section adjacent the curved portions which are bent over normally of the plane of the section in the manner illustrated in Fig. 5.

It is believed obvious from the foregoing description that the door may be used in an opening in an interior wall of a building to separate two rooms and of such width that when the door is opened the two rooms become a unit. The device may also be used on a small scale as a closet door.

The subject matter of Figs. 1-8 in the present application is disclosed and claimed in my co-pending patent application Serial Number 80,906, filed March 11, 1949, of which the present application is a divisional part thereof.

The claims hereinafter set forth are specifically directed to the portion of the invention shown in Figs. 9 and 10, which relate to a foldable closure for an opening in a building wall in conjunction with a pair of upright channelled trackways 4 of the same construction shown in Figs. 1 and 7.

By the construction shown in Figs. 9 and 10, the door is opened and closed by vertical raising and lowering. However, the construction of the door and its hingedly interconnected sections is exactly the same as that above described in connection with Figs. 1-8. Furthermore, the linkages 13 and their pivotal connections between the various sections are exactly the same as that above described in connection with Figs. 1, 2 and 6. The various sections 17 which make up the vertically movable door are of exactly the same structure as above described in connection with Figs. 1, 2, 3, 4 and 5.

The formation of the flange plates upon the opposite ends of the door sections, upon opposite sides thereof, corresponding to the direction of the corresponding curved portions of said sections as at 19, is exactly the same as above described in connection with Figs. 1-5. The connection of the pins 10 with the brackets 18 upon the door sections 17 is exactly the same as above described in connection with Figs. 1 and 8, except that the brackets 18 are arranged at the opposite ends of sections 17 as shown in Fig. 10.

The only difference between the structure of Fig. 10 and the structure described in connection with Figs. 1-8 is that the door sections as interconnected are movable vertically instead of horizontally, and furthermore instead of one set of guide rollers 7 and 8 whereby the door sections were suspended in Fig. 1, there are provided similar guide rollers at the opposite ends of each of the sections 17 which are vertically movable within the opposed channel trackways 4 which are arranged in an upright position upon the sides of the door opening.

Furthermore, it will be noted that there is provided a horizontally elongated bracket 16 at the upper end of the door opening in Fig. 10, which is secured to the adjacent wall, and which has a downwardly depending arcuately formed longitudinal portion 18' adapted to cooperatively receive

4

in overlapped relation a similarly formed longitudinal edge portion of the upper-most section 17', which is of less width than the other section 17. It is apparent furthermore that there are depending flanges 3' at the opposite ends of bracket 16 which are pivotally connected as at 2' to the corresponding flanges 25 of the uppermost door section 17'.

The door may be progressively raised and lowered manually by the handle 22 shown in Fig. 10 in the same manner as said handle is employed for opening and closing the door shown in Fig. 1. It is contemplated that a mechanical device could be employed for raising the lowermost door section 23, which in turn would effect a corresponding progressive elevation of the other door sections 17.

Fig. 9 shows a central securing bracket 26 which depends from the upper central portion of the building wall above the door opening and whose lower end projects inwardly of said opening as at 27 to retainingly engage the lowermost section 23 for holding the same and the collapsed door in its upper-most open position.

Having described my invention, reference should now be had to the claims which follow for determining the scope thereof.

I claim:

1. In a foldable closure for an opening in a building wall including opposed upright channelled trackways upon opposite sides of said opening, a plurality of elongated upright door sections of sheet metal, a horizontally directed pin mounted centrally upon the opposite end edges of each section, rollers swivelled upon said pins and movably mounted and supported within said trackways for suspending said door sections within said opening and for guiding the vertical opening and closing movements of said sections, the opposite longitudinal edge portions of each section throughout their length being curved outwardly in opposite directions from the opposite faces of said sections, the corresponding curved edges of adjacent sections being arranged in overlapped engagement with each other, flange plates at the opposite ends of said edge portions at right angles to the planes of said sections and extending in the direction of the corresponding curve portion, means pivotally interconnecting adjacent flange plates of adjacent sections whereby said sections may be elevated along said trackways and foldably collapsed into substantial parallel engaging relation adjacent the top of said building opening, a horizontally elongated bracket secured to said wall along the top of said opening, parallel flanges depending downwardly from the opposite ends of said bracket at right angles thereto, and parallel flange plates at the upper opposite ends of the upper-most section at right angles thereto and pivotally joined to and suspended from said bracket flanges.

2. In a foldable closure for an opening in a building wall including opposed upright channelled trackways upon opposite sides of said opening, a plurality of elongated upright door sections of sheet metal, a horizontally directed pin mounted centrally upon the opposite end edges of each section, rollers swivelled upon said pins and movably mounted and supported within said trackways for suspending said door sections within said opening and for guiding the vertical opening and closing movements of said sections, the opposite longitudinal edge portions of each section throughout their length being curved outwardly in opposite directions from the opposite faces of

said sections, the corresponding curved edges of adjacent sections being arranged in overlapped engagement with each other, the opposite end edges of each section corresponding to the opposite ends of said edge portions being bent over normally of the plane of said sections in the direction of the corresponding curved portion defining flanged plates which are overlapped between sections, and means pivotally interconnecting said plates whereby said sections may be foldably collapsed into parallel engaging relation, there being a bracket at the top of said building opening, the flanged plates at the upper opposite ends of the upper-most section being pivotally suspended upon said bracket.

3. In a foldable closure for an opening in a building wall including opposed upright channelled trackways upon opposite sides of said opening, a plurality of elongated upright door sections of sheet metal, a horizontally directed pin mounted centrally upon the opposite end edges of each section, rollers swivelled upon said pins and movably mounted and supported with said trackways for suspending said door sections within said opening and for guiding the vertical opening and closing movements of said sections, the opposite longitudinal edge portions of each section throughout their length being curved outwardly in opposite directions from the opposite faces of said sections, the corresponding curved edges of adjacent sections being arranged in overlapped

engagement with each other, parallel spaced vertical flange plates extending normally from the opposite end edges of said sections adjacent said edge portions and upon the opposite sides of each section corresponding to the direction of each curved portion, the corresponding flanges of adjacent sections being arranged in overlapped relation, means pivotally interconnecting said plates whereby said sections may be elevated along said trackways and foldably collapsed into substantial parallel engaging relation adjacent the top of said building opening, a horizontally elongated bracket secured to said wall along the top of said opening, and parallel flange plates at the opposite ends of the upper-most section at right angles thereto and pivotally joined to and suspended from the opposite ends of said bracket.
